UNITED STATES PATENT OFFICE.

FRANK GRAY, OF CHESTER, PENNSYLVANIA.

DESIGN FOR A BADGE.

SPECIFICATION forming part of Design No. 26,966, dated April 27, 1897.

Application filed February 13, 1897; Serial No. 623,326. Term of patent 14 years.

To all whom it may concern:

Be it known that I, FRANK GRAY, of Chester, Pennsylvania, have invented certain new and useful Designs in Badges, of which the following is a specification.

My invention relates to designs in badges; and it consists in the configuration and shape, as shown in the drawing, which will be more fully described hereinafter.

10 A represents the bar, from which depends, by two short chains B, the plate or shield C, upon the center of which is superimposed a Passion cross F, and upon this Passion cross is superimposed a Maltese cross G, each of contrasting colors. From opposite sides of the 15 upper end of the Passion cross the represen-

tation of rays of light is shown as proceeding from the center. The shield is also provided with a marginal border-line.

The field of the shield between the Passion 20 cross and the border-line affords suitable space for letters, designs, or legends, as desired.

Having thus described my invention, I claim--

25 The design for a badge, substantially as shown and described.

FRANK GRAY.
